US00D496794S1

(12) **United States Design Patent** (10) Patent No.: **US D496,794 S**
Del Solar (45) Date of Patent: **** Oct. 5, 2004**

(54) **SURFACE PATTERN FOR ABSORBENT PAPER**

(75) Inventor: **Renato Del Solar**, Mannheim (DE)

(73) Assignee: **SCA Hygiene Products GmbH**, Mannheim (DE)

(**) Term: **14 Years**

(21) Appl. No.: **29/178,411**

(22) Filed: **Mar. 27, 2003**

(30) **Foreign Application Priority Data**

Sep. 27, 2002 (DE) 4 02 08 255

(57) **CLAIM**

The ornamental design for a surface pattern for absorbent paper, as shown and described.

DESCRIPTION

The sole FIGURE is a top plan view of my new design for a surface pattern for absorbent paper. The surface pattern is within the broken lines and is understood to be repeated uniformly throughout the length and width of the absorbent paper. The broken lines form no part of the design.

1 Claim, 1 Drawing Sheet
